UNITED STATES PATENT OFFICE.

ANTON M. KNUDSEN, OF CHICAGO, ILLINOIS, AND KARSTEN KNUDSEN, OF GRAND RAPIDS, MICHIGAN.

TELAUTOGRAPH.

No. 920,966.

Specification of Letters Patent.

Patented May 11, 1909.

Application filed March 12, 1906. Serial No. 305,536.

To all whom it may concern:

Be it known that we, ANTON M. KNUDSEN, a citizen of the United States of America, and resident of Chicago, county of Cook, 5 and State of Illinois, and KARSTEN KNUDSEN, a citizen of the United States of America, and resident of Grand Rapids, county of Kent, and State of Michigan, have invented a new and useful Improvement in 10 Telautographs, of which the following is a specification.

Our invention herein described and illustrated, lies in circuits and apparatus for transmitting handwriting and the like electrically to a distance.

The plan of our invention is that a tracing point at a writing station may follow substantially the movements of a tracing point at a distant controlling station, the medium 20 of control being alternating or pulsating current or the like.

This specification is accompanied by nine figures, in which—

Figure 1 shows the circuits of a line having an equipment at each end in accordance with our invention; Fig. 2 shows mechanical and electrical detail of the equipment involved in Fig. 1. Fig. 3 shows an alternative circuit for accomplishing the same results. Fig. 4 shows an alternative method of attaching the tracing point, either of the controlling instrument or of the writing instrument, to the armatures or cores of the electrical helices. Fig. 5 shows a possible 35 method of connection between the tracing point and the armatures or cores of any machine. Fig. 6 shows another method of connecting the tracing point with the armatures or cores of the electrical helices. Fig. 7 40 shows detail of the laminated core and the electrical helix in one of the three magnets shown in Fig. 6. Fig. 8 shows a method of adjustment for the magnets of Fig. 6, and Fig. 9 shows a simple paper feed device.

Like numbers represent like parts throughout the several views.

In Fig. 1, 1 is a three-phase alternating current generator, having three terminals, 10, 11, 12; 2 is an electrical switch adapted 50 to have its members separated by the lifting of the tracing point or pen at the controlling instrument, and by reason of its control by the pen it will be called hereafter the pen switch; 3 is the device for controlling the

electrical conditions over the line conductors, 55 7, 8, 9, and will be referred to hereafter as controller or transmitter; 4 is a switch, referred to hereafter as the control switch, for changing the conditions of the entire equipment at one end of the line from controlling 60 or transmitting conditions to receiving conditions, or vice versa; 5 is the device for recording the electrical transmission, this device remaining in circuit with the line conductors at all times and serving to leave a record 65 of the transmission sent out from its own station as well as the transmission received from the distant station or stations; 6 is a feed relay adapted to feed intermittently a 70 paper, tape, or the like, upon which the transmission may be recorded by the tracing points, proper control for the feed devices being provided, as later described herein; 7, 8 and 9 are the line conductors, the earth being shown as line conductor 9; 6', 5', 75 4' are similar parts of apparatus located at the station at the end of the line distant from that end equipped with 1, 2, 3, 4, 5, 6. When earth is used as a line conductor, balancing resistances, impedances, etc., may 80 be included in the ground legs, as is practiced in multiple telegraphy, where balancing is required. The ends of the line are equipped fully with similar apparatus, that either may transmit to the other, but in Fig. 85 1 the end to the right is shown operative to transmit to the end to the left, and the end to the left is shown with its control switch 4' in that position to remove its controlling or transmitting mechanism from the line circuits and to leave its receiving apparatus 90 operative, the parts 3', 2', 1', being omitted from the figure to give greater convenience in drawing the parts shown.

The plan of operation is as follows: The 95 tracing point of the controller 3 is moved by the hand of the operator; such movement on the part of the tracing point of the controller 3 causes electrical conditions to be set up over the line conductors 7, 8, 9, such 100 that the tracing points of the receiving instruments 5, 5', and such other similar instruments as may be in circuit, are influenced to move in a direction and to an extent corresponding to the direction and extent of the movement of the tracing point of the controller 3; the movement of the tracing point of the controller 3 thus is 105

duplicated in the receiving instruments, being duplicated in the receiving instrument associated with the active controller as well as in the distant receiving instrument shown in the drawing, and in such other receiver instruments as may be connected in the line circuits, whether with or without transmitting controllers. The means by which this cooperation of movement between controller and receiver is obtained is as follows: The tracing point 30 of the controller 3, as shown in Fig. 2, is associated mechanically with the cores or plungers of the three helices 31, 32, 33, of the controller, and the tracing point 50 of the receiver 5 is associated with the armatures of three helices 51, 52, 53, arranged angularly similarly to the corresponding helices of the controller. Homologous helices of the two devices are connected in series, and thence the circuit extends through homologous helices of such other receiving instruments as it may be desired to control, the circuits being completed as shown in diagram in Fig. 1. Helices 31, 32 and 33 are helices of variable impedance, the impedance being controlled by the further insertion or partial or complete withdrawal of the cores or plungers shown in connection with the respective helices and associated with the tracing point 30 by pivotal connections. Helices 51, 52 and 53 are electromagnets adapted to be responsive to alternating currents, and they may be of any desired mechanical construction; their armatures are associated with each other and with the tracing point 50 as clearly shown diagrammatically in Fig. 2, and as shown further in detail in Figs. 4, 5 and 6. As shown in Fig. 2, a strengthening of the magnetic field of any receiver helix would draw the armature or plunger further into the helix and thus push the tracing point 50 away from the helix thus energized above the degree of energization of the remaining two helices. In the controller of Fig. 2 the operating power of the device is manual and not electrical, so that the movement of the tracing point toward any helix would pass the plunger of that helix farther into the winding and at the same time withdraw partially or wholly the remaining two plungers from their helices; thus the impedance would be increased in that helix toward which the tracing point 30 is moved, while the impedance would be correspondingly decreased in those remaining helices from which the tracing point had moved. As the flow of alternating current through a given conductor depends to some degree upon the absence or degree of impedance in the conductor, this variation of impedance in the various helices at the controller will produce reversed variations in the flow of alternating current in the corresponding line conductors, with

consequent influence upon the magnetic fields of the corresponding helices of the associated and connected receiving apparatus; our operation now may be traced definitely as follows, referring at the same time to Figs. 1 and 2: With the controller tracing point at rest, current will flow from the three-phase generator 1 equally through the following paths: first 13, 11, 2, 31, 51, 6, 8, 6', 51', 41', 42', 52', 6', 9', earth, 9, 6, 52, 32, 2, 10; second 14, 12, 33, 53, 6, 7, 6', 53', 43', 41', 51', 6', 8, 6, 51, 31, 2, 11, and third 15, 10, 2, 32, 52, 6, 9, earth, 9', 6', 52', 42', 43', 53', 6', 7, 6, 53, 33, 12. These three currents are approximately equal because the three line limbs 7, 8, 9 are approximately equal in all respects, and the three controlling impedances, 31, 32, 33, of the controller 3, are approximately equal in impedance because of the equal insertion of the cores or plungers with the tracing point 30 in the middle position, which is its normal position of rest.

If the tracing point 30 of the controller be advanced, say toward the helix, 33, the plunger will be inserted farther into helix 33 and the plungers will be withdrawn to a certain extent from the helices 31 and 32; thus the impedance of the helix 33 will be increased and the impedance of the helices 31 and 32 respectively will be reduced. The increase of impedance in helix 33 will reduce the current flowing through helices 33, 53 and 53'; the reduction of impedance in helix 31 will increase the current flowing through helices 31, 51 and 51'; the reduction of impedance in helix 32 will increase the current flowing through helices 32, 52 and 52'; thus the helix 53 of the receiver 5 will attract its armature less strongly, while the helices 51 and 52 of that receiver will attract their armatures more strongly, with consequent overpowering to a certain extent of the armature of helix 53 by the combined attraction of the armatures of helices 51 and 52 and with consequent motion of the tracing point 50 toward the helix 53, that movement being homologous both in direction and extent to the motion of the tracing point 30 toward the helix 33 in the controller 3. This movement of the tracing point 50 of the receiver 5 will be duplicated in all of the receivers connected in the circuit. By assuming any position of the tracing point 30 and studying the resulting impedance and currents, it will be seen that the tracing point 50 will assume a homologous position in the receiver 5, and thus the tracing point 50 of the receiver 5 will follow continuously the movements of the tracing point 30 of the controller 3.

Thus we have seen how, by the use of our invention, the controlling point at 30 may cause the writing point at 50 to trace letters, words and the like, at a distant point, to the

limit of movement of the tracing points as governed by the armatures or plungers of the associated helices.

To enable the writing point to write continuously for extended periods, thus transmitting communications of considerable length, we have devised means by which the sheet of paper written on may be caused to pass under the tracing point, rather than a means whereby the tracing point may pass continuously over the sheet written upon.

A paper ribbon or tape, 16, fed from the roll 17, passes under the controlling point 30 and then under the writing point 50 of the associated receiver; thence it passes between friction rollers 18 and 19, the roller 18 being driven by clockwork as indicated. The roller 18 has rigidly attached to it a ratchet 20 with teeth so spaced that by the progress of the ratchet from one tooth to the next the paper ribbon will be advanced one unit step of desired length. The clockwork tends to draw the paper ribbon continuously forward; the ratchet prevents the movement when its teeth are engaged by pawls, of which pawls two are provided, one as a projection on lever 21, pivoted at 22, and carrying the armature of electromagnet 23, and the other as a projection on lever 24, pivoted at 25, and carrying the armature of electromagnet 26. Contact pair 27 tends to stand open, but is closed when pressed by a projection from arm 24; contact pair 28 tends to stand open, but is closed when pressed by a projection from arm 21. The two arms, 21 and 24, are interlocking at 29. In Fig. 2, arm 24 is shown held down by arm 21, and the pawl of arm 21 is restraining ratchet 20. If, now, electromagnet 23 is energized, arm 21 will be drawn down, releasing ratchet 20 and releasing arm 24, and arm 24 rises to engage and restrain ratchet 20 and also to interlock at 29 to prevent arm 21 from rising.

Attached to tracing point 30 is an arm 35 passing through pivoted block 36, the arm 35 permitting free motion of the tracing point 30 in the plane of the surface of the paper ribbon without moving the block 36, but if the pen be lifted from the surface of the paper ribbon the pivoted block 36 will be moved upon its pivots, and consequently will move the arm 37, to operate the pen switch 2, the arm 37 being rigidly fixed in the block 36. Thus when the tracing point or pen 30 is lifted from the surface of the paper ribbon, the pen switch 2 is operated to open its two electrical conductors, the pen switch 2 being operated to close its conductors again when the pen or tracing point 30 is again pressed into contact with the paper ribbon 16. By the lifting from the paper of the tracing point 30, the pen switch 2 is operated to open its conductors, and thus no current may flow over the line conductors; thus

relay 6 is deenergized and armature 61 is released, closing contact 63 and permitting current to flow from battery 34 through 61-63-27 and winding of electromagnet 23, energizing electromagnet 23, attracting its armature and moving arm 21, releasing ratchet 20 and stepping the paper ribbon forward one step, but also by the interlocking feature at 29 the arm 24 is released to rise and stop the ribbon movement at the end of the one step; also, the rise of arm 24 has opened electrical contact pair 27, interrupting the battery circuit just described and has closed contact pair 28. Upon pressing tracing point 30 into contact with the surface of the paper ribbon, pen switch 2 closes its conductors, thus permitting currents to flow over the line conductors, energizing relay 6, attracting its armature 61 and closing contact between 61 and 62, giving path for current through circuit 34, 61, 62, winding of electromagnet 26, 28, etc., attracting its armature, moving arm 24, and releasing ratchet 20 to move the paper tape another step; but the movement of arm 24 has released arm 21 to stop the paper ribbon at the end of one step; release of arm 21 also opens electrical contact pair 28, interrupting the battery circuit just described, and closes contact pair 27. Thus by lifting the tracing pen 30 from the paper tape, the tape has been stepped forward a predetermined distance, presenting a new surface for writing, both by tracing point 30 and tracing point 50. It may be mentioned at this point that points 30 and 50 write upon the same tape, but may write upon different portions of it, as one upon the upper and the other upon the lower edge of the tape, thus not interfering with each other. This step of the paper tape written upon occurs at all of the receiving instruments connected in the circuit, as is indicated in the drawing of the relay 6' at Fig. 1. An additional feature involved in the lifting of the point 30 from the paper tape is that by so doing, and by the consequent movement of arm 21, the writing table under tracing point 50 is depressed, thus breaking the contact between tracing point 50 and the paper tape, to correspond in all essential details to the breaking of contact between the tracing point 30 and the paper tape.

An alternative form of paper feed is shown in Fig. 9, in which the paper tape 16 is drawn forward step by step by the action of a pawl 101 affixed directly to the armature 61 of the magnet 6 without intermediary electrical apparatus, the separation of the paper and the tracing point being accomplished by attaching the writing table 102 directly to the armature 61. Upon deenergization of the magnet 6 the armature 61 is released and the pawl 101 drops into a succeeding tooth of the ratchet 20. The rolls 18-19 are not associated with the ar-

mature 61 other than through the pawl 101 and the ratchet 20. Upon the reenergization of the magnet 6, the armature 61 is attracted and by its movement acts through 5 the pawl 101 to revolve the ratchet 20 and thus to draw the paper tape 16 forward a unit step.

Fig. 4 shows a pantograph attachment by 10 which the tracing point 30 may be brought away from the associated levers, helices and plungers to make it more convenient for the operator's hand. The apparatus shown in Fig. 4 may be considered and described as a modification of controller 3 of Fig. 2. 15 The tracing point 30 of Fig. 2 is modified in Fig. 4 by the omission of the tracing element and by the addition of two pantograph arms 103—104. Two additional pantograph arms 105—106 are provided. 20 The arm 105 is attached pivotally to a fixed member at 107; arms 103—105 are pivotally attached to each other at 108; arms 105—106 are pivotally attached to each other at 109; arms 104—106 are pivotally attached to 25 each other at 110; and arm 106 carries a tracing point 111. It is evident that the movement of the tracing point 111 by the hand of the operator will result in a corresponding movement of the junction point 30, corresponding to the tracing point 30 of Fig. 2.

In Figs. 4 and 5 the diagrammatic construction of Fig. 2 is elaborated in showing a system of levers between the tracing point 30 and the helices 31—32—33, whereby the weight of the plungers is so disposed as to move vertically while the tracing point 30 may move to write in a horizontal plane. The helix 32 is shown in section in Fig. 5 35 and a bell crank lever 112 is pivoted at 113. This bell crank lever is associated by the link 114 with the plungers 32^a of the helix 32, and is associated by the link 115 with the junction point or tracing point 30. Fig. 40 shows a plan view of this arrangement.

Fig. 6 shows a plan of an arrangement of magnets having rotary armatures instead of solenoid plungers. In Fig. 6 the helices are designated 31—32—33 to correspond to the 50 diagram of Fig. 2. Each helix has a laminated core and return pole piece 31^a—32^a—33^a and between the poles of this core are pivoted the armatures 31^b—32^b—33^b. Each pivoted armature is rigidly attached to 55 a rocker arm 31^c—32^c—33^c which connects through a link 31^d—32^d—33^d with the tracing point 30.

Fig. 7 shows elevation of the helix 33 and its laminated core and return pole piece 33^a, 60 the armature and associated parts being removed.

Fig. 8 shows a method of screw adjustment by which the power of any magnet of the device of Figs. 6 and 7 in its action upon 65 its armature may be changed. The screw

and nut 65 is attached to the core 66 and passes through a rigid part 116. By turning the nut of the part 65 the core 66 may be drawn nearer to the fixed part 116 and thus may be drawn away from its armature 70 67, reducing the influence of a given current upon that armature. By reversing the direction of movement of the nut of the part 65, the spiral spring 117 is permitted to press the core 66 nearer to the armature 67, 75 thus increasing the magnetic effect.

The currents required for the operation 80 of this system may be defined as only such as are susceptible of influence by change in the inductance of their circuits; this permits the use of alternating currents, as illustrated, or pulsating or interrupted currents, pole-changer currents, and the like. Such currents may be defined briefly as varying currents.

In addition to provision in the grounded limb of the line for balancing by means of impedance and resistance, similar provision likely will be required for possible use in any or all of the limbs of the line circuit, to 90 provide for the successful operation of the system over faulty lines, and the like, but these adjustments, being of a nature well understood in telephony and telegraphy of the present day, are not herein discussed.

The angles between the axes of the various helices is not a limiting detail of my invention, as a plurality of helices may be provided with angles of any size or sizes, it being shown here with three helices and 100 120° angles as a simple form.

In Fig. 3 is shown an alternative circuit for the operation of the devices as shown. In this circuit a source of suitable current 38 has a bus wire 39 passing through the 105 open switch 40 and thence to all of the helices, as 31, 32, 33, in multiple, the circuit being extended by a separate line conductor from each of the controlling helices to its corresponding recording helix or helices in the connected receiver or receivers; at the distant end of the transmission line the circuits again group upon a common return, 110 41.

We do not wish to limit ourselves in all respects, to the specific details herein described and illustrated, as we understand that our apparatus is capable of many modifications without departing from the spirit or scope of our invention.

Having thus described our invention, what 120 we claim as new and wish to secure by United States Letters Patent, is:

1. In a telautograph, a transmitter, a receiver, a recording ribbon, a step-by-step ribbon feed, and means by which said ribbon feed is rendered operative by lifting the tracing point of said transmitter from the writing table, substantially as described.

2. In a telautograph, a transmitter; a receiver; a receiving tape; a step-by-step tape

feed; a relay in the line circuit at said receiver and relay-controlling contacts in the line circuit at said transmitter, said relay-controlling contacts operating by the lifting 5 of the transmitter stylus from its tape and said relay operating to produce a step-by-step feed of said receiving tape, substantially as described.

3. In a telautograph, a transmitter; a 10 stylus at said transmitter; electrical contacts at said transmitter; a receiver; a receiving tape; a step-by-step tape feed at said receiver controlled by electrical contacts at said transmitter; and a pivoted arm 15 associated with said contacts and the stylus of said transmitter whereby by the lifting of said stylus said contacts will be broken, substantially as described.

4. In a telautograph, a transmitter; a 20 receiver; a receiving tape; a step-by-step tape feed; a relay in the line circuit at said receiver and relay-controlling contacts in the line circuit at said transmitter, said relay-controlling contacts operating by the lifting 25 of the transmitter stylus from its tape and said relay operating to produce a step-by-step feed of said receiving tape; and means whereby the writing pen of the receiver and the receiving tape are separated while the 30 writing stylus is lifted, substantially as described.

5. In a telautograph, the combination of a transmitter having three impedance units of variable inductance and spaced radially 35 at equal angles; a receiver having electromagnets in number and position corresponding to said impedance units; and means for varying the inductance of said impedance units, substantially as described.

40 6. In a telautograph, the combination of a transmitter having more than two impedance units of variable inductance, the links of which are spaced radially at equal angles at the tracing stylus; a receiver having electromagnets in number corresponding to said 45 impedance units and the operating links of which are spaced at corresponding angles at the writing pen; and means for varying the inductance of said impedance units, substantially as described.

50 7. In a telautograph, the combination of a transmitter having three impedance units of variable inductance and spaced radially at equal angles; a receiver having electromagnets in number and position corresponding 55 to said impedance units; means for varying the inductance of said impedance units; three conductors connecting said transmitter and said receiver; and a source of three-phase alternating current connected through 60 said three impedances to three line conductors and thence to said transmitter, substantially as described.

8. In a telautograph, the combination of

a transmitter having three variable inductances, the operating connections of which approach a tracing stylus at equal angles; a line of three conductors; and a source of three-phase alternating current connected through said inductances to said line, substantially as described. 65

9. In a telautograph transmitter, a plurality of inductance units; a tracing point; plungers associated with said inductance units and adapted to vary the inductance 70 thereof respectively; and connections between said plungers and said tracing point whereby movement of said tracing point will cause corresponding movement of said plungers, said impedances being more than 75 two in number and said connections approaching said tracing point in directions making substantially equal angles with each other, substantially as described.

10. In a telautograph, a receiver having 80 three electromagnets in triangular arrangement; a three-conductor line; a three-phase generator connected through said line to said units; and variable inductances to control the current flow, substantially as described. 85

11. In a telautograph transmitter, a plurality of impedance units, each having a variable self-inductance; armatures, one for each of said impedance units, said armatures 90 being adapted by the position thereof with reference to the magnetic circuit of the impedance units to vary the inductance of each impedance unit; a tracing point; mechanical connections between said tracing 95 point and said armatures whereby the relative inductance of said impedances is controlled by the position of said tracing point; a multi-conductor line; and a multi-phase alternating-current generator connected 100 through said impedances to said line, the number of phases of said generator, the number of conductors of said line and the number of impedances being all equal, substantially as described. 105

12. In a telautograph, a three-phase alternating-current generator; three line conductors; three inductive units through which the energy of said generator may be impressed upon the said line conductors; a receiver having three electromagnets; and means for varying the relative inductances of said inductive units, substantially as described. 110

13. In a telautograph, a multi-phase alternating-current generator; a plurality of line conductors; a plurality of inductive units through which the energy of said generator may be impressed upon the said line conductors; means for varying the relative inductance of said inductive units; and a receiver having a plurality of electromagnets; the number of line conductors, induct- 120

ive units and electromagnets respectively being severally equal to the number of phases in said generator, substantially as described.

14. In a telautograph, a three-phase alternating-current generator; three line conductors; three inductive units through which the energy of said generator may be impressed upon the said line conductors; a receiver having three electromagnets; and means for varying the relative transmission of energy through said inductive units, substantially as described.

15. In a telautograph, a multi-phase alternating-current generator; a plurality of line conductors; a plurality of inductive units through which the energy of said generator may be impressed upon the said line conductors; and means for varying the relative transmission of energy through said inductive units; a receiver having a plurality of electromagnets; the number of line conductors, inductive units and electromagnets respectively being severally equal to the number of phases in said generator, substantially as described.

16. In a telautograph, the combination of a transmitter having a plurality of impedance units of variable inductance; a receiver having a similar number of electromagnets; a transmission line having a similar number of conductors, and a multi-phase alternating-current generator, the number of whose phases is equal to the number of said impedance units, the transmission circuits including said generator, said impedance units and said receiver electromagnets, and said impedances being of manually variable inductance, substantially as described.

17. In a telautograph receiver, a writing point; and three receiving electromagnets, said writing point being attached to all the armatures thereof; said receiving magnets acting upon said writing point in three different directions, each direction making an angle greater than ninety degrees with either of the other two directions when the directions are taken within a plane parallel to the plane of writing, substantially as described.

18. In a telautograph receiver, a writing point; and a plurality of receiving electromagnets, said writing point being attached to all the armatures thereof; said receiving magnets being more than two in number and acting upon said writing point each in opposition to two remaining magnets, substantially as described.

19. In a telautograph receiver, a writing point; and three receiving electromagnets, said writing point being attached to all the armatures thereof; said receiving magnets acting upon said writing point in three different directions, each direction making an angle greater than ninety degrees with either of the other two directions when the directions are taken within a plane parallel to the plane of writing, and said writing point being held in any position by reason of an equilibrium established by and among the several armatures collectively, and being moved from position to position by a readjustment of the relative intensities of the fields of said electromagnets, substantially as described.

20. In a telautograph receiver, a plurality of receiving electromagnets; an armature for each of said electromagnets; said armatures being connected in equilibrium each against others under the attraction of said electromagnets when energized; and a writing point connected with said armatures, substantially as described.

21. In a telautograph receiver, a plurality of receiving electromagnets; connected armatures therefor pulling each against others under the magnetism of said electromagnets when energized; and a writing point in connection with said armatures, substantially as described.

22. In a telautograph receiver, a plurality of receiving electromagnets; armatures for said electromagnets and connected together and pulling each against others under the magnetism of said electromagnets and in equilibrium under the magnetism of said electromagnets when the magnetism of said electromagnets is not changing; and a writing point in connection with said armatures, substantially as described.
